Primary Examiner — Prabhakar Deshmukh*(74) Attorney, Agent, or Firm* — Rader, Fishman & Grauer PLLC(57) **CLAIM**

The ornamental design for a vehicle panel, as shown and described.

DESCRIPTION

FIG. 1 is a perspective view of a vehicle panel showing our new design;

FIG. 2 is a front elevational view thereof;

FIG. 3 is a left side elevational view thereof;

FIG. 4 is a right side elevational view thereof;

FIG. 5 is a top plan view thereof; and

FIG. 6 is a bottom plan view thereof.

FIG. 7 is a perspective view of another embodiment of a vehicle panel showing our new design;

FIG. 8 is a front elevational view thereof;

FIG. 9 is a left side elevational view thereof;

FIG. 10 is a right side elevational view thereof;

FIG. 11 is a top plan view thereof; and

FIG. 12 is a bottom plan view thereof.

FIG. 13 is a perspective view of yet another embodiment of a vehicle panel showing our new design;

FIG. 14 is a front elevational view thereof;

FIG. 15 is a left side elevational view thereof;

FIG. 16 is a right side elevational view thereof;

FIG. 17 is a top plan view thereof; and,

FIG. 18 is a bottom plan view thereof.

Portions in broken lines are for illustrative purpose only and form no part of the claimed design. The dot-dash broken lines define but are not included in, the boundaries of the claimed design.
